UNITED STATES PATENT OFFICE.

JEREMIAH M. HAYDEN, OF GRAND RAPIDS, MICHIGAN.

DESIGN FOR A BLOCK OF METAL.

SPECIFICATION forming part of Design No. 30,469, dated April 4, 1898.

Application filed November 2, 1898. Serial No. 695,324. Term of patent 14 years.

To all whom it may concern:

Be it known that I, JEREMIAH M. HAYDEN, a citizen of the United States, residing at Grand Rapids, in the county of Kent and State of Michigan, have invented a new and original Design for a Block of Metal, of which the following is a specification.

My invention relates to a new and original design for a block of metal and is shown in the accompanying drawing, which is a perspective view.

The leading feature of my design consists in a block of metal in the form of a truncated cone, with a segment of a sphere or globe rising from its top surface and separated from the circumference by a surrounding annular flat surface, as shown.

In the said drawing the reference-numeral 1 indicates the block of metal, which is in the form of a truncated cone, as shown at 2. The

numeral 3 designates the segment of a sphere or globe rising from the top surface of the said truncated cone, and 4 designates the annular flat surface surrounding said segment of sphere or globe and separating it from the circumference of the truncated cone.

My design presents a block of metal of novel and distinguishing appearance.

Having thus described my invention, what I claim is—

The design for a block of metal herein shown and described.

In testimony whereof I have hereunto set my hand in presence of two subscribing witnesses.

JEREMIAH M. HAYDEN.

Witnesses:

EDWARD TAGGART,
CHRISTOPHER HONDELINK.
